(57) **CLAIM**

I claim the ornamental design for the ratchet pawl for a thumbwheel actuated stent delivery system, as shown and described.

DESCRIPTION

FIG. 1 is a front view of a ratchet pawl for a thumbwheel actuated stent delivery system according to the present design;

FIG. 2 is a right side view of the ratchet pawl of FIG. 1;
 FIG. 3 is a rear perspective view of the ratchet pawl of FIG. 1;

FIG. 4 is a front perspective view of the ratchet pawl of FIG. 1; and,

FIG. 5 is a rear view of the ratchet pawl for a thumbwheel actuated stent delivery system of FIG. 1 as seen in the environment of a thumbwheel stent delivery system.

The claim is understood to comprise only the shaded surfaces of the ratchet pawl.

The features shown with dashed lines are for environmental purposes only and form no part of the claimed design.
